UNITED STATES PATENT OFFICE

FRANKLIN L. FOULKS, OF MOUNT HOLLY, NEW JERSEY

BODY-HANDLING DEVICE

Application filed October 1, 1926. Serial No. 138,907.

My invention relates to a body-handling device for use by undertakers and the like.

My main purpose is to facilitate the moving of a body from a bed or other raised position to and into an undertaker's body-basket.

A further purpose is to handle dead bodies in a manner more quiet, easy, orderly, rapid and sanitary than has hitherto been possible.

10 A further purpose is to handle the body without the need for more than one person, thus dispensing with the assistance of a helper.

15 A further purpose of my invention is to mount a body-table so that it can conveniently be lifted from and lowered into a body-basket, receiving the body for the basket upon the table while the table is raised, then sinking the table and the body into the basket for 20 transfer to an undertaker's establishment, ordinarily to an embalming table.

A further purpose is to hinge the spaced pairs of legs of a body-table at one end to the bottom of a body-basket, and at the other 25 end to the bottom of a body-table, adapting the table to disappear into the basket and to reappear therefrom, preferably latching the table in raised position.

30 A further purpose is to provide an emergency embalming table within a body-basket.

Further purposes will appear in the specification and in the claims.

I have elected to show one form only, with a slight modification among the many 35 forms in which the invention may appear. I have selected a form that is efficient and practical in operation, inexpensive to manufacture, and which well illustrates the principles involved.

40 Figure 1 is a side elevation in part section, showing my body-lifter applied to a body-basket.

Figure 2 is a top plan view of the structure 45 shown in Figure 1.

Figure 3 is a vertical longitudinal section of the basket with the device in side elevation and lowered within the basket, a partly raised position being shown in outline.

50 Figures 4 and 5 are sections respectively of

Figure 1 taken upon the line 4—4 and Figure 3 taken upon line 5—5.

Figure 6 is a view corresponding to Figure 2 but showing a slight modification.

Figure 7 is a side view, partially in section, 55 of the modification shown in Fig. 6.

Like numerals refer to like parts in all figures.

Describing in illustration and not in limitation and referring to the drawings,— 60

In the past when removing a dead body from a hospital, sanitarium, private residence or elsewhere to an undertaking establishment, the transfer of the body to and from the ambulance basket has been accomplished with some difficulty and frequently with rough handling of the body that has been distasteful to friends and relatives of the dead, and that has involved for the undertakers an unnecessary amount of time and 65 physical labor and at times dangerous contact with the body.

The ambulance-basket has been set alongside of the body and two or more men have then lifted the body from the bed into the 70 basket during which it has sometimes happened that the body, particularly when very large has fallen heavily into the basket. A second handling, with incidental heavy tugging and lifting has been necessary to transfer 75 the body from the basket to the embalming table.

80 My invention is directed toward alleviating this unfortunate and distasteful condition.

I combine a body receiving table with a body-basket. In transferring a body from a bed to the basket the table is raised from the inside of the basket to the level of the bed 85 upon which the body is lying, and is held in that position. The body is then easily slid from the bed to the table.

90 After the body has been received upon the table the table is swung quietly down into the basket for transfer to the undertaking establishment or elsewhere, where it is again swung up to present the body in a suitable position for easy removal or for an embalming operation. Some form of latch is prefer- 95 100

ably used to hold the table reliably when in raised position.

Heavy handling of the body with its indecorous tugging and lifting is thus avoided both at the hospital and at the undertaking establishment.

In the structure shown the body-basket 14 has wicker sides 15 and a stiff wooden bottom 16, which comprises the usual ambulance or body-basket, and my table and body-handling structure is securely mounted upon the bottom of this basket.

Spaced angle pieces 17 and 18 are fastened at 19 to the bottom of the basket. Spaced 15 pairs of legs 20, best seen in Figures 1 and 4, are hinged at the bottom at 21 to the angles 17 and 18 and at the top at 22 to the underside of the table 23. The legs of each pair are united to form a rigid unit or frame by suitable cross pieces forming braces 24 and 25 of suitable material, which are riveted to the opposite legs at 26. These cross braces are desirably light flats and the legs light angles.

The table is desirably of rolled sheet 25 aluminum, strengthened at the sides by turning down flanges 27. Preferably the metal is raised at 28 as by a rib, along each edge. This raised portion serves the double purpose of affording additional stiffening 30 and strengthening of the table is preferably provided by suitable angles 29 and 30 riveted to the lower side of the table along opposite sides. They afford convenient connections for pivoting the legs to the table.

35 The front and rear pairs of legs are preferably alike and are hinged at the bottom to the same pair of angles 17 and 18. These angles are bolted to the bottom of the basket preferably upon each side of the hinges.

40 I show a latch to hold the table in raised position and comprising one or more sets of folding tie links 31 and 32 respectively hinged at 33 to one of the bottom angles and at 34 to one of the legs and pivotally connected at 35. One or both of the links are notched at 36 some little distance inwardly from the pivot 35 between the links, to receive a transversely extending lug 37 upon the other link. These lugs 37 register with the respective 45 notches and engages the links at the bottom of the notches to limit the opening motion of the combined tie to 180°, and thus latch the legs in vertical position when the table has been fully raised.

55 The latch is loosened by means of a chain 38 which is connected to one of the links at 39, passed to and around a pulley 40 upon the lower side of the table and thence along the 60 under side of the table toward the head of the table where it is suitably supported in the table so that it can be operated by a ring 41. This causes the links 31 and 32 to swing toward the table. A handle 42 is provided 65 at each end of the table, the table being

raised or lowered by taking hold of one or both of these handles.

When the table is nearly raised, in some such position as shown in outline in Figure 3, the vertical support from the legs becomes 70 markedly more noticeable and the continued movement becomes a nearly horizontal swinging movement requiring little strength. In raised position one end 43 overlaps the corresponding end of the basket to a distance 75 determined nearly by the length of the legs.

When the table is swung down the tie links 32 and 33 fold up and the legs fold down between the bottom of the basket and the table.

Normally the upper surface of the table 80 need be only one or two inches above the bottom of the basket when the table is down, so that the folding table structure may be used with the normal basket, being preferably removably mounted on the bottom of the basket. 85

The form shown in Figures 6 and 7 is the same in principle and in general operation as that shown in the earlier figures, the only differences being a slight modification of the table and of the mounting legs and a slightly 90 different fastening mechanism for holding the table in raised position.

The hinges 21' and 22' secure the legs to the baseboard within the basket and to the table 23' respectively, and the fastening device comprises a rod 31' pivoted to the table at 44 and terminating in a prong 45 which engages the baseboard within the basket. The rod is lifted by means of chain 38' terminating in ring 41 as in the other form. 100

One practical advantage of my invention lies in the relief which it offers from the awkwardness and clumsiness in the handling of the bodies by which a considerable part of the strength of the attendants in the past 105 has been required, so that all of the strength of an attendant may now be applied to the best advantage to the lifting and swinging of the table, or to restraining it against excessive downward speed of movement by reason of 110 the weight of the body.

The table is desirably made of aluminum both because of the lightness thus secured and because aluminum is very easily cleaned and is resistant to rusting and corrosion. Other 115 metals and wood are also quite acceptable.

A considerable advantage of my structure lies in the ease with which it may be kept clean. Any blood or other fluid comes upon a metal surface that is readily cleaned instead of upon the wooden bottom of the basket or upon the wicker work of the basket which is more difficult to clean.

In view of my invention and disclosure 125 variations and modifications to meet individual whim or particular need will doubtless become evident to others skilled in the art, to obtain all or part of the benefits of my invention without copying the structure shown, and I, therefore, claim all such in so far as 130

they fall within the reasonable spirit and scope of my invention.

Having thus described my invention, what I claim as new and desire to secure by Letters Patent is:—

- 5 1. In a combined body basket and handling or operating table, a body basket, a body table and connections therebetween adapting the table to be raised from inside the basket, to a position above the basket to receive a body and then to be lowered again into the basket with the body in place upon it, the connections being suited to hold the table in raised position.
- 10 2. In a combined body basket and handling or operating table, a body basket having a bottom, a body table smaller than the inside horizontal cross-section of the basket and adapted to fit in the basket, and mechanism for supporting the table well above the basket permitting the table to be raised reliably from or lowered and guided into the basket.
- 15 3. In a combined body basket and handling or operating table, a basket, a table adapted to fit therein, spaced pairs of legs hinged at opposite ends respectively to the table and to the basket adapted to pivotally carry the table along an arc from inside the basket near the bottom thereof to near the vertical position of the legs, a pair of tie links pivotally fastened together at adjoining ends and having their other ends respectively pivotally fastened to the bottom of the basket and to one of the legs at a distance from the hinge of the leg, adapted to fold flat between the table and the bottom of the basket when the table is in the basket and to limit the arcuate swing of the table when the table is raised, a latch limiting the relative angular motion of the links to that corresponding to raised position of the table, and means for loosening the latch.
